UNITED STATES PATENT OFFICE.

THOMAS E. MONROE, OF BROOKLYN, NEW YORK.

AUTOMATIC PLAYER-PIANO.

1,212,240.

Specification of Letters Patent.

Patented Jan. 16, 1917.

Application filed April 23, 1915. Serial No. 23,546.

To all whom it may concern:

Be it known that I, THOMAS E. MONROE, a citizen of the United States, and a resident of the borough of Brooklyn, in the city and State of New York, have invented certain new and useful Improvements in Automatic Player-Pianos, of which the following is a specification.

The invention relates to automatic player pianos, and has for its principal object to provide means whereby certain notes of a tune may be automatically played louder than the other notes in the tune, and whereby the excess of loudness of such notes over the remainder of the tune may be regulated at the will of the operator.

The invention consists in the novel construction, arrangement and combination of devices, elements and parts, as shown in the accompanying drawings, and fully described in this specification.

In the said drawings, Figure 1 is a fragmentary front view of a tracker-bar such as I employ, also showing a fragmentary portion of my perforated music-sheet; Fig. 2 is a transverse vertical section of auxiliary pneumatic devices used in carrying my invention into effect; Fig. 3 is a longitudinal vertical section of the same, taken on the line 3—3 of Fig. 2, and looking in the direction of the arrows; Fig. 4 is a fragmentary bottom view taken on the line 4—4 of Fig. 2 and Fig. 5 is a view of a fragment of a modified form of music sheet, as hereinafter particularly described.

In the rendering of music, it is often desirable that the air, or main portion of the composition, be given greater prominence than the secondary portion, or accompaniment, and that the relative intensity of these two portions of the piece may be varied by the operator at will. To secure the best results, he should also be able to vary the force of the whole series of notes in the air, as such, and of the whole series of accompaniment notes as such, independently at will while he is playing the music, playing the accompaniment softly while he is playing the air more loudly. In carrying my invention into effect, in the embodiment thereof which I have selected for illustration in the accompanying drawings, and description in this specification, I achieve these ends as follows: I provide a player-piano, having strings, hammers, and other mechanism, and having the usual pneu-

matic operating devices. The tracker-bar which I employ (see Fig. 1) is designated 8. This tracker-bar is similar to those used on ordinary player-pianos, provided with air ports 7 which control the striking mechanism. This tracker-bar, however, is provided with an additional series of ports 9, preferably located above or in advance of said first named ports, these ports controlling the pneumatic mechanism to be hereinafter described. I provide also a perforated music-sheet 5, provided with slits 11. Certain of these slits, (those controlling notes which it is desired to emphasize) are provided at their lower ends with offsets 10. It will be observed that the ordinary slits, which are not provided with offsets, will as the sheet travels downward over the tracker-bar, open only portions of certain of the main ports 7. When, however, a slit provided with an offset 10 moves over the tracker-bar, it first opens a port 9 to its full extent, and after having passed thereover, opens the corresponding port 7 to its full extent for a short time, subsequently cutting down the width of this opening to the width of the ordinary slit, at which width it is maintained as long as the slit leaves the port 7 uncovered.

Instead of providing perforations having offsets, as above described, I may provide a music sheet as shown in Fig. 5 in which, for the offsets are substituted independent auxiliary perforations 50 located substantially as an offset would be, but separated from the adjacent main perforations 51 by an unperforated portion of the material of the music sheet. I also provide the usual hammers, designated 29, which are mounted on shafts 34, pivoted at 32, and provided with surfaces 33 adapted to receive the impact of rods 35. These hammers strike against strings 31, and their extreme backward movement is limited by the stop 36. These hammers are also provided with portions 27 provided with surfaces 28 adapted to be engaged by the pawls 23 hereinafter to be described.

The ports 7 of the tracker-bar 8 are provided with ducts 3 leading to the usual pneumatic hammer-striking mechanism. The ports 9 are provided with flexible ducts 12 leading through passages 13, to diaphragm chambers 14. There is one diaphragm chamber for every port 9, and each chamber is connected by means of a com-

paratively small vent 21 with a suction chest 22, which is in turn connected by means of a flexible tube to the main suction chest of the piano (not shown on the drawing.) The chambers are preferably arranged in a 5 double row, as shown in the drawings, for the sake of economizing space.

Each chamber 14 is provided with a diaphragm 15, having a downwardly projecting screw 17 secured in a washer 16. I also provide for every chamber 14 a lever 19, pivoted at 20. This lever is provided with an upwardly extending screw 38, which is connected with the screw 17 by means of a turnbuckle 18. Each lever 19 is provided at one end 15 with a weight 25, and at the other with a movable pawl 23, pivoted thereto at 24, and normally held in the position shown by a spring 26. The entire diaphragm mechanism, levers and exhaust box 22 are supported by uprights 39. These uprights have their lower ends pivoted at 32, and are capable of moving about said pivot to a limited extent, as indicated by the dotted lines in 25 Fig. 2, carrying the diaphragm mechanism with them. These uprights may be operated by any suitable means (not shown in the drawings) which may, for example, terminate in a handle outside the piano case and within reach of the operator's hand.

30 The operation of my invention is as follows: When the piano is not in use, the uprights 39 are inclined to their full extent toward the left of Fig. 2, the diaphragms 15 being exposed to atmospheric pressure on both sides, are under no tension, and assume approximately the position shown in the right-hand chamber of Fig. 2, being held in this position by the weights 25 on the levers 19. The end of the lever 19 bearing the weight 25 being depressed, the other end bearing the pawl 23 is raised, and the said pawl is out of engagement with the surface 28. The hammers occupy the position shown 35 at the left of Fig. 2, resting on the stop 36. When it is desired to operate the piano, the 40 perforated music-sheet 5 is inserted in the usual manner, and the pneumatic bellows of the piano put in operation. A suction is thereby created in the chamber 22, and as the 45 chambers 14 communicate therewith, and as their communication with the outer air through the ports 9 is cut off by the music-sheet, a suction is created in the chambers 14, and the diaphragms 15 are raised against the force of the weight 25, depressing the 50 pawls 23 into engagement with the surfaces 28 connected with the hammers 29. The uprights 39 are then moved into a position approximately as shown in Fig. 2, by means of 55 the external handle previously described. This moves the diaphragms and mechanism connected therewith into a position approximately as shown in Fig. 2, and the pawls 23 60 being in a depressed position, the hammers

are moved into the right-hand position as shown. As the music-sheet 5 travels downward over the tracker-bar 8, certain of the ports 7 will be from time to time uncovered for varying intervals of time, thus operating 75 the hammers 29 by means of the rods 35 in the usual manner. As long, however, as none of these slits are provided with offsets 10 or auxiliary perforations 50, the suction in the chambers 14 will be maintained, and the pawls 23 will remain depressed. Thus 80 the hammers 29 will be played from the position shown at the right of Fig. 2, and, owing to the shortness of the stroke, and the short duration of the blow from the rod 35, the 85 blow of the hammer will be a light one, such as is suitable for an accompaniment. The intensity of this blow may be varied by moving the uprights 39 either toward the right or toward the left of Fig. 2, by means 90 of the external handle mentioned above, in a manner which will be well understood. When, however, a slit with an offset or an auxiliary perforation 50 passes over the tracker-bar, one of the ports 9 is uncovered, 95 and air is admitted to the chamber 14 with which said port communicates. As the inlet of said chamber is considerably larger than the outlet, it follows that when the inlet is uncovered the chamber will almost immediately fill with air, and remain full as long as the inlet remains uncovered, but that when the inlet is again covered it will be emptied through the opening 21. As air is admitted 100 to one of these chambers 14 by the uncovering of the port 9 connected therewith, the pressure on the outside of the diaphragm 15 is equalized, and under the action of the weight 25, the diaphragm drops into the position shown at the right of Fig. 2, operating 105 to raise its pawl 23, and allowing the hammer previously held by said pawl to drop back against the stop 36. The slit 11, with its offset 10, continues to move over the tracker-bar, until a port 7 is uncovered. The 110 hammer 27, being then played from the stop 36, owing to the greater length of its stroke and the greater duration of the blow of the rod 35, the impact will be considerably greater than if the hammer were played 115 from the pawl 23, and the sound correspondingly louder. The intensity of these notes may be varied in the usual well-known manner. It will be understood that the series of 120 ports 9 must be sufficiently in advance of the series 7 to permit the former to operate and release the hammers and still allow the pawled levers to drop again into holding position before a hammer rebounds after 125 striking a string, so that on such rebound the hammer may be again caught and held by its pawl.

130 It will be observed that the pawls 23 are pivoted to the levers 19 at 24, and normally held in the position shown in the drawings

by a spring 26. Although when the hammer is played from the stop 36, the pawl 23 is normally out of the way, yet it sometimes happens that a hammer may be resting upon 5 stop 36 when its pawl 23 is in its lowered position, as for instance, if the operator forgetfully moves the uprights 39 forward before starting the suction, or if after the raising of a pawl 23 it should resume its position 10 before the note is played. If this should happen, the hammer may still be played from the stop 36, as the hammer in its passage will pass the pawl 23, its impact being sufficient to bend the spring 26 and raise the 15 pawl the latter resuming its normal position after the hammer is past. The pawl 23 should drop back into place before the hammer 27 drops away from the string 31. The backward stroke of the hammer is thus arrested 20 by the said pawl, and it will not again be played from the stop 36 unless the pawl is again raised. By means of the turnbuckle 18, the normal position of the lever 19 may be properly adjusted, so that the pawl 23 25 will normally be in engagement with the surface 28, but will clear same when the pawl-bearing end of the lever 19 is raised.

The advantages of my invention are obvious. It will be seen that by the structure 30 shown and described, it is possible to play the notes of the melody or main portion of the composition with a certain intensity, and the accompaniment or supplementary portion with a different intensity, and to vary at 35 will the absolute and relative intensities of these two sets of notes, thus enabling proper expression to be put into the rendering of the piece.

Having thus described my invention, what 40 I claim as new and desire to secure by Letters Patent is as follows:

1. In a player piano, the combination with strings, hammers, means for operating said hammers and a tracker bar provided 45 with a series of ports operatively connected with said hammer-actuating mechanism; of a suction-chamber, a series of auxiliary suction chambers each provided with a diaphragm, a channel between said first named 50 suction chamber and each of said auxiliary suction-chambers, devices operatively connected with each of said diaphragms and adapted to hold one of said hammers from moving backward when said diaphragm is in one position and to release 55 said hammer and permit the same to move backward when said diaphragm is in another position, a second series of ports in said tracker bar, and a channel connecting each port of said second series with one of said auxiliary suction 60 chambers.

2. In a player piano, the combination with strings, hammers, means for operating said hammers and a tracker bar provided with a 65 series of ports operatively connected with

said hammer-actuating mechanism; of a suction-chamber, a series of auxiliary suction-chambers each provided with a diaphragm, a channel between said first named suction chamber and each of said auxiliary 70 suction chambers, a channel between each of said auxiliary suction chambers and the open air, devices operatively connected with each of said diaphragms and adapted to hold one of said hammers from moving backward 75 when said diaphragm is in one position and to release said hammer and permit the same to move backward when said diaphragm is in another position, and a second series of ports in said tracker bar, said second series 80 of ports opening into said second named channels.

3. In a player piano, the combination with strings, hammers, means for operating said hammers and a tracker bar provided with 85 a series of ports operatively connected with said hammer actuating mechanism; of a suction chamber, a series of auxiliary suction chambers each provided with a diaphragm, a channel between said first named 90 suction chamber and each of said auxiliary suction chambers, a channel between each of said auxiliary suction chambers and the open air, said second named channels being larger than said first named channels, devices 95 operatively connected with each of said diaphragms and adapted to hold one of said hammers from moving backward when said diaphragm is in one position and to release 100 said hammer and permit the same to move backward when said diaphragm is in another position, and a second series of ports in said tracker bar, said second series of ports opening into said second named channels.

4. In a player piano the combination with strings, hammers, means for operating said hammers, and a tracker bar provided with a series of ports operatively connected with 105 said hammer-actuating mechanism; of a suction-chamber, a series of auxiliary suction-chambers each provided with a diaphragm, a second series of ports in said tracker bar, a channel connecting each of said second series of ports with one of said auxiliary suction 110 chambers, a channel connecting each of said auxiliary suction-chambers with said first named suction-chamber, said channel being smaller than the channel between said auxiliary suction-chamber and said tracker 115 bar, and devices operatively connected with each of said diaphragms, and adapted to hold one of said hammers from moving backward when said diaphragm is in one position and to release said hammer and permit the same to move backward when said 120 diaphragm is in another position, said hammer-holding devices comprising a lever one end of which is adapted to engage with said hammer.

5. In a player piano the combination with strings, hammers, means for operating said hammers and a tracker bar provided with a series of ports operatively connected with said hammer-actuating mechanism; of a suction-chamber, a series of auxiliary suction-chambers each provided with a diaphragm, a second series of ports in said tracker bar, a channel connecting each of said second series of ports with one of said auxiliary suction-chambers, a channel connecting each of said auxiliary suction-chambers with said first named suction-chamber, said channel being smaller than the channel between said auxiliary suction-chamber and said tracker bar, and devices operatively connected with each of said diaphragms, and adapted to hold one of said hammers from moving backward when said diaphragm is in one position and to release said hammer and permit the same to move backward when said diaphragm is in another position, said hammer-holding devices comprising a lever provided with a pawl at one end adapted to engage with said hammer.

6. In a player piano the combination with strings, hammers, means for operating said hammers and a tracker bar provided with a series of ports operatively connected with said hammer-actuating mechanism; of a suction-chamber, a series of auxiliary suction-chambers each provided with a diaphragm, a second series of ports 30 in said tracker bar, a channel connecting each of said second series of ports with one of said auxiliary suction-chambers, a channel connecting each of said auxiliary suction-chambers with said first named suction-chamber, said channel being smaller than the channel between said auxiliary suction-chamber and said tracker bar, and devices operatively connected with each of 35 said diaphragms, and adapted to hold one of said hammers from moving backward when said diaphragm is in one position and to release said hammer and permit the same to move backward when said diaphragm is in another position, said hammer-holding devices comprising a lever provided with 40 a weight at one end and a pawl at the other end adapted to engage with said hammer. 45

7. In a player piano the combination
with strings, hammers, means for operat-
ing said hammers and a tracker bar pro-
vided with a series of ports operatively con-
nected with said hammer-actuating mech-
anism; of a suction-chamber, a series of
auxiliary suction-chambers each provided
with a diaphragm, a second series of ports
in said tracker bar, a channel connecting
each of said second series of ports with one
of said auxiliary suction-chambers, a chan-
nel connecting each of said auxiliary suc-
tion-chambers with said first named suction-

chamber, said channel being smaller than the channel between said auxiliary suction-chamber and said tracker bar, and devices operatively connected with each of said diaphragms, and adapted to hold one of said hammers from moving backward when said diaphragm is in one position and to release said hammer and permit the same to move backward when said diaphragm is in another position, said hammer-holding devices comprising a lever having at one end a pawl adapted to engage with said hammer, and an adjustable link between said lever and said diaphragm.

8. In a player piano, the combination 80
with strings, hammers, means for operating
said hammers and a tracker bar provided
with a series of ports operatively connected
with said hammer-actuating mechanism; of
a suction-chamber, a series of auxiliary suc- 85
tion-chambers each provided with a dia-
phragm, a second series of ports in said
tracker bar, a channel connecting each of
said second series of ports with one of said
auxiliary suction-chambers, a channel con- 90
necting each of said auxiliary suction-
chambers with said first named suction-
chamber, said channel being smaller than
the channel between said auxiliary suction-
chamber and said tracker bar, and devices 95
operatively connected with each of said dia-
phragms, and adapted to hold one of said
hammers from moving backward when said
diaphragm is in one position and to release
said hammer and permit the same to move 100
backward when said diaphragm is in an-
other position, said hammer holding devices
comprising a lever and a pawl pivotally
mounted on said lever adapted to engage
with said hammer. 105

9. In a player piano the combination with said hammer-actuating mechanism; of a suction-chamber, a series of auxiliary suction-chambers each provided with a diaphragm, a second series of ports in said tracker bar, a channel connecting each of said second series of ports with one of said auxiliary suction-chambers, a channel connecting each of said auxiliary suction-chambers with said first named suction-chamber, said channel being smaller than the channel between said auxiliary suction-chamber and said tracker bar, and devices operatively connected with each of said diaphragms, and adapted to hold one of said hammers from moving backward when said diaphragm is in one position and to release said hammer and permit the same to move backward when said diaphragm is in another position, said hammer-holding devices comprising a lever, a pawl pivotally mounted on said lever adapted to engage 130

with said hammer, and a spring adapted to normally hold said pawl in engaging position.

10. In a player piano the combination with 5 strings, hammers, means for operating said hammers and a tracker bar provided with a series of ports operatively connected with said hammer-actuating mechanism; of a suction-chamber, a series of auxiliary suction chambers each provided with a diaphragm, a second series of ports in said tracker bar, a channel connecting each of said second series of ports with one of said auxiliary suction-chambers, a channel connecting each of said auxiliary suction-chambers with said first named suction-chamber, said channel being smaller than the channel between said auxiliary suction-chamber and said tracker bar, and devices operatively 15 connected with each of said diaphragms, and adapted to hold one of said hammers from moving backward when said diaphragm is in one position and to release said hammer and permit the same to move backward when said diaphragm is in another position, said hammer-holding devices comprising a lever, a pawl pivotally mounted on said lever adapted to engage with said hammer, a spring adapted to normally hold 20 said pawl in engaging position, and a stop adapted to prevent said pawl from rotating in one direction.

11. In a player piano, the combination with strings, hammers, means for operating 35 said hammers, and a tracker bar provided with a series of ports operatively connected with said hammer operating means; of a second series of ports in said tracker bar, and means operatively connected with said 40 ports and adapted when in one position to hold one of said hammers from moving backward and when in another position to release said hammer, said means comprising a lever provided with a pawl at one end adapted to engage with said hammer.

12. In a player piano, the combination with strings, hammers, means for operating said hammers, and a tracker bar provided with a series of ports operatively connected 50 with said hammer operating means; of a second series of ports in said tracker bar, and means operatively connected with said ports and adapted when in one position to hold one of said hammers from moving backward and when in another position to release said hammer, said means comprising a lever provided with a weight at one end and a pawl at the other end adapted to engage with said hammer.

13. In a player piano, the combination with strings, hammers, means for operating said hammers, and a tracker bar provided with a series of ports operatively connected with said hammer operating means; of a second 55 series of ports in said tracker bar, and means

operatively connected with said ports and adapted when in one position to hold one of said hammers from moving backward and when in another position to release said hammer, said means comprising a lever and 70 a pawl pivotally mounted on said lever adapted to engage with said hammer.

14. In a player piano, the combination with strings, hammers, means for operating said hammers, and a tracker bar provided with a 75 series of ports operatively connected with said hammer operating means; of a second series of ports in said tracker bar, and means operatively connected with said ports and adapted when in one position to hold one of said hammers from moving backward and when in another position to release said hammer, said means comprising a lever, a pawl pivotally mounted on said lever adapted to engage with said hammer, and a 80 spring adapted to normally hold said pawl in engaging position.

15. In a player piano, the combination with strings, hammers, means for operating said hammers, and a tracker bar provided with a 90 series of ports operatively connected with said hammer operating means; of a second series of ports in said tracker bar, and means operatively connected with said ports and adapted when in one position to hold one of 95 said hammers from moving backward and when in another position to release said hammer, said means comprising a lever, a pawl pivotally mounted on said lever adapted to engage with said hammer, a 100 spring adapted to normally hold said pawl in engaging position, and a stop adapted to prevent said pawl from rotating in one direction.

16. In a player piano, the combination 105 with strings, hammers, means for operating said hammers, and a tracker bar provided with a series of ports operatively connected with said hammer operating means; of a second series of ports in said tracker bar, 110 means operatively connected with said ports and adapted when in one position to hold one of said hammers from moving backward, and when in another position to release said hammer, said means comprising 115 a lever provided with a pawl at one end adapted to engage with said hammer; and a music sheet adapted to pass over said tracker bar and provided with perforations, some of which perforations are adapted to 120 uncover only ports of said first named series and other of which perforations are adapted to uncover ports of said second named series.

17. In a player piano, the combination 125 with strings, hammers, means for operating said hammers, and a tracker bar provided with a series of ports operatively connected with said hammer operating means; of a second series of ports in said tracker 130

bar in advance of said first named series of ports, means operatively connected with said ports and adapted when in one position to hold one of said hammers from moving 5 backward and when in another position to release said hammer, said means comprising a lever provided with a pawl at one end adapted to engage with said hammer; and a music sheet adapted to pass over said 10 tracker bar and provided with perforations, some of which perforations are adapted to uncover only ports of said first named series and other of which perforations are adapted to uncover ports of said second 15 named series.

18. In a player piano, the combination with strings, hammers, means for operating said hammers, and a tracker bar provided with a series of ports operatively connected 20 with said hammer operating means; of a second series of ports in said tracker bar, each port of said second series being narrower than the ports of said first named series, means operatively connected with 25 said ports and adapted when in one position to hold one of said hammers from moving backward and when in another position to release said hammer, said means comprising a lever provided with a pawl at one 30 end adapted to engage with said hammer; and a music sheet adapted to pass over said tracker bar and provided with perforations, some of which perforations are adapted to uncover only ports of said first named series 35 and other of which perforations are adapted to uncover ports of said second named series.

19. In a player piano, the combination with strings, hammers, means for operating 40 said hammers, and a tracker bar provided with a series of ports operatively connected with said hammer-actuating means, of a second series of ports in said tracker bar, each port of said second series being

narrower than and in advance of a portion 45 of the corresponding port of the first named series, means operatively connected with said ports and adapted when in one position to hold one of said hammers from moving backward and when in another position 50 to release said hammer, said means comprising a lever provided with a pawl at one end adapted to engage with said hammer; and a music sheet adapted to pass over said 55 tracker bar and provided with perforations, some of which perforations are adapted to uncover only ports of said first named series and other of which perforations are adapted to uncover ports of said second 60 named series.

20. In a player piano, the combination with strings, hammers, means for operating said hammers, and a tracker bar provided with a series of ports operatively connected 65 with said hammer actuating means; of a second series of ports in said tracker bar, each port of said second series being narrower than and in advance of a side of the corresponding port of the first named series, means operatively connected with said ports 70 and adapted when in one position to hold one of said hammers from moving backward and when in another position to release said hammer, said means comprising a lever provided with a pawl at one end 75 adapted to engage with said hammer; and a music sheet adapted to pass over said tracker bar and provided with perforations, some of which perforations are adapted to uncover only ports of said first named series 80 and other of which perforations are adapted to uncover ports of said second named series.
